UNITED STATES PATENT OFFICE.

ANTOINE E. M. PRENVEILLE AND DONALD E. PRENVEILLE, OF OAKLAND, CALIFORNIA.

SLIDING GRATE FOR OVENS.

Application filed August 4, 1924. Serial No. 729,945.

Our invention relates to sliding oven-grates of the type which are arranged to be drawn outwardly from or replaced in the oven by the opening or closing movement of the oven-door.

An object of the invention is to provide means entirely controlled by the oven-door handle for permitting the grate to remain within the oven or caused to be withdrawn from the oven by the movement of the oven-door when the latter is opened.

Another object of the invention is to provide grate supporting means which will effectively support the grate in all of the extended positions thereof, and which will be fully concealed within the oven when the grate is entirely drawn back therein.

The invention possesses other objects and features of advantage some of which with the foregoing will be set forth in the following description of the preferred form of our invention which is illustrated in the drawings accompanying and forming part of the specification. It is to be understood, however, that we do not limit ourselves to the showing made by the said drawings and description as we may adopt variations of the preferred form within the scope of our invention as set forth in the claims.

Referring to said drawings:

Figure 1 is a vertical sectional view thru an oven equipped with the grate of our invention, the grate being shown entirely within the oven, and the door being shut.

Figure 2 is a view similar to Figure 1, showing the door fully opened, and the oven in extended position.

Figure 3 is a plan view of a portion of the inner side of the door in extended position showing the door connecting and releasing means for the grate.

Figure 4 is a sectional view on the line 4—4 of Figure 1.

As illustrated in the drawings, the device of our invention is associated with an oven 4 of a design such as is usually incorporated in stoves and ranges. The opening 5 at the front of the oven is arranged to be closed by a suitable door 6 hinged to swing about a horizontal pivot 7 preferably located in a plane just below the bottom 8 of the oven and forwardly of the plane of the opening 5. The door is arranged to swing outwardly and downwardly to the position indicated in Figure 2 and is provided with a handle 9

similar to the usual type of oven-door handle of stoves and comprising spaced brackets 11 between which is held a grip 12.

Suitably fixed within the oven and preferably provided at each of the opposite sides thereof, are frame pieces 13 each of which has fixed thereto a guideway 14 here shown of channel cross section. Slidably carried by the guideways 14 are tracks 16 which as here shown are also of channel cross section and are arranged to fit within the channel of the guideways.

Preferably of a length slightly less than the depth of the oven is a grate member 17 which, as here shown, is in the form of a grate rack or holder. For convenience, however, the member 17 will be hereinafter referred to as the grate, it being further understood that said member may be in the form of an oven bottom or other equivalent member on which articles within the oven may be supported. The grate, adjacent its bottom, is preferably provided with bars 18 which are arranged to slidably fit in the channels of the movable tracks 16. The bars 18, tracks 16 and guideways 14, are preferably of about the same length as the grate, and the two first mentioned members are preferably adapted to fit practically entirely within the guideway when the grate is completely within the oven. On the other hand, when the grate is drawn outward from the oven the track and bars are arranged to move outwardly from the guideway. Furthermore, the bars may move outwardly from the track, and in this manner, by properly limiting the outward movement of the bars with respect to the track and, limiting the outward movement of the latter with respect to the guideways, the grate may be effectively supported in a position practically on the outside of the oven, since in effect the track thus serves as a cantilever support.

In accordance with the foregoing, the bar 18 is preferably provided with a stop 19 which is arranged to engage a cooperating stop 21 formed at the forward edge of the track when the grate has been moved to a position about half way out on the track; in addition, the track is preferably provided at its rear edge with a stop 22 which is arranged to engage a shoulder 23 preferably provided mediate of the guideway.

Means, arranged to be controlled entirely

by movement of the door handle grip, are provided for causing the opening and closing movement of the door to effect an outward or inward movement of the grate relative to the oven. Pivoted to the frame piece just above and inwardly of lower forward edge of the oven is a bell-crank lever 24, one arm 25 of which is arranged to extend upwardly along the inner side of the door when the grate is retracted and the door is closed, while the other arm 26 is arranged to extend inwardly into the oven substantially parallel to the bottom thereof. The inner end of the arm 26 is attached, by means of a pin and slot connection, to a link 28 which is pivoted to a lever 29 fulcrumed to the frame piece adjacent the rear wall 30 of the oven. The lever 29 is connected to a lever 31 by means of a link 32, the lever 31 being pivoted at one end to the frame piece at a point adjacent the top of the oven mediate of the front and rear thereof, and the other end being pivoted to a link 33 which is attached to the grate at the lower forward edge thereof. It will now be noted that by swinging the lever arm 25 outwardly to assume the horizontal position, as indicated in Figure 2, the grate will be caused to move from a fully retracted position to an extending position wherein it is practically completely withdrawn from the oven. It will furthermore be noted that with the lever system as illustrated, the lever 25 will move through an angle of 45° from its vertical position before appreciable outward movement of the grate is effected. Reversal of the movement of the lever, that is from the lower to the upper position, will obviously cause the above described actuation of the grate in the reverse order.

As previously mentioned, the foregoing means for moving the grate is arranged to be actuated by the movement of the door and controlled by appropriate manipulation of the door handle. Slidably mounted in bearings 34 provided on the inner side of the door adjacent the top edge 35 is a bolt member 37 having catches 38 provided thereon and arranged to be caused to engage extensions 39 provided on the free ends of the lever arms 25. When the door is vertically disposed, or, in other words, in closed position, the catches 38, due to the weight of the bolt, will lie in depressed position and thus be out of engagement with the extensions 39 of the lever 25. With the members thus disposed, movement of the door will in no way effect the grate. However raising of the bolt, it will be noted, will serve to effect the operative engagement of the catches with the lever 25, and thus cause the before described movement of the grate upon movement of the door. As here shown, the raising of the bolt is arranged to be effected by rotating the grip portion 12 of the handle. The grip

is mounted for manual rotation about a shaft 41 suitably fixed in the handle brackets 11. Fixed for movement with the grips is a pair of fingers 42 which are arranged to extend through slots 43 provided in the door and to engage the under side of the bolt. In this manner, by merely grasping the grip and slightly rotating the same to raise the fingers, the catches will engage the extensions, and movement of the door will then cause the movement of the grate. Owing to the fact that the pivotal axes of the oven door and the bell crank lever 24 are spaced, they preferably, and as here shown, define a plane making an angle of substantially 45 degrees with the oven bottom whereby the lever arm 25 may maintain a nearly parallel relation to the door when swung therewith in the manner indicated and may be parallel thereto when the door is closed or fully open. Owing to the foregoing relation of the pivotal axes of the door and lever, it will now be clear that as the door is opened with the extensions 39 engaged in front of the catches 38, the arms 25 and their extensions 39 will move radially inwardly along the door and so fix the arms to the door independently of any manipulation of the door handle. In this manner, the door handle need be manipulated and held to dispose the bolt catches 38 behind the extensions 39 only at the beginning of the opening operation, since an automatic engagement is effected by and upon the opening operation itself.

The fingers are preferably formed with shoulders 44 which serve to cover the portions of the slots not closed by the fingers. In order to insure the disengagement of the catches from the extensions when the door is closed, the forward edges of the extensions 39 are bevelled near the bottom thereof.

We claim:

1. The combination with an oven and a door therefor, of a grate mounted to slide into and out of said oven, means arranged to be connected to the door and grate to cause the grate to be moved out of and into the oven upon the opening and closing movement of the door, a handle for said door comprising a bracket positioned on the outer side of the door, a grip member supported by said bracket for rotation about an axis parallel to the plane of said door, and an arm extending through the door and movable upon rotation of said grip member to connect said means to the door or disconnect same therefrom.

2. In combination with an oven and a door therefor, a grate member slidably mounted in said oven for rectilinear movement therein and arranged to be moved to and be supported in a position substantially entirely outwardly therefrom, means arranged to be actuated by the opening and

closing movement of the door for sliding said grate respectively out of and into the oven, portions of said grate operating means being movable relative to the door 5 and arranged to lie outwardly of said oven when said door is in intermediate and fully opened positions and to be maintained in substantially parallel relation to said door.

3. In combination with an oven and a 10 door therefor, a grate member mounted to slide into and out of said oven, a bell-crank lever mounted in said oven and having an arm releasably secured to said door and ar-

ranged to extend outwardly of said oven when said door is in intermediate and fully 15 opened positions, to maintain a parallel relation to said door, and means operatively connecting the other arm of said lever to said grate whereby the grate may be moved out of and into the oven upon the opening 20 and closing movement of the door.

In testimony whereof, we have hereunto set our hands at Oakland, California, this 1st day of July, 1924.

ANTOINE E. M. PRENVEILLE.
DONALD E. PRENVEILLE.
